MACHINE FOR TREATING HIDES, SKINS,
LEATHER, AND OTHER SIMILAR PIECES
OF WORKKarl Rausch, Dresden, Germany, assignor to The
Turner Tanning Machinery Company, Port-
land, Maine, a corporation of MaineApplication April 10, 1933, Serial No. 665,318
In Germany June 3, 1932

11 Claims. (Cl. 149—15)

This invention relates to machines for treating hides, skins, leather, and other similar pieces of work. While the invention is illustrated as embodied in a machine for graining and/or softening pieces of leather it is to be understood that the invention and various important features thereof may have other applications and uses.

In my copending application, Serial No. 609,633, filed May 6, 1932, there is disclosed a boarding machine comprising boarding rolls one of which is constructed in such manner that an intermediate portion of the roll is cylindrical in shape while the end portions thereof are conical or tapered, the arrangement being such that the relative lengths of the cylindrical and tapered portions may be altered to suit different pieces or classes of work.

Pieces of leather suitable for graining operations are, in fact, tanned skins, the denser, finer portions of which lie along each side of the backbone line of the skin. The width of this finer, denser portion of the skins varies with each skin, as does also the width of the thinner, loosely textured flank portions of the skin. These flank portions should not be operated upon at the same pressure as the finer, denser portions nearer the backbone line of the skin. It will be understood that there is no distinct line of demarcation between the finer, denser portions and the thinner, loosely textured portions of the skin but that there is a gradual change from one to the other. Hence, the tapered ends of the roll are suited to apply the required pressure since the taper of such end portions is also gradual. Since each skin differs from every other skin in size, and in the amount of loosely textured flank portions in comparison with the finer, denser portion thereof, it is advantageous to be able to vary at will the amount of taper of the rolls and of the length of this tapered portion relatively to the cylindrical portion of the roll, as shown in my aforesaid copending application. It is also advantageous, as herein disclosed, to be able to vary instantly the degree of taper of the roll so that the roll may be suited to each individual piece of work, if such should be necessary or desirable. Ordinarily the skins will be sorted more or less carefully so that adjustment of the tapered roll will be made for different batches of skins rather than for each individual skin, but even then facility of adjustment is a distinctly desirable feature.

In those cases in which it is desired to send the skins through the machine a second time to obtain a boxing effect upon the grain surface

such skins are introduced for the second operation by placing them over the work support in such manner that they are supported along the backbone line or along a line adjacent and substantially parallel to the said backbone line. For operating upon a skin so placed both boarding rolls should be cylindrical throughout, the pressure of the rolls being suitably adjusted as, for instance, through treadle means disclosed in my copending application mentioned above. This fact constitutes another reason for employing a boarding roll having special provision for adjustability.

To these ends and in accordance with an important feature of the invention, a work treating roll comprising a cylindrical portion and also conical or tapered end portions is provided with manually operable means for adjusting both tapered portions of the roll simultaneously in such manner that the tapered portions of the roll may be varied relatively to the intermediate cylindrical portion of the roll, the arrangement being conveniently such that the tapered portions may be completely effaced whereby the roll becomes cylindrical throughout. By the provision of such a manually operable means the work treating roll may be adjusted instantly even while the machine is in operation to suit each piece of work presented to the machine, and to secure various desirable results. As illustrated the adjusting means comprises cam members movable in directions lengthwise of the roll and operable to increase or diminish the diametric dimensions of a conical or tapered end of the roll.

In a preferred construction, the roll comprises longitudinally extending members and supporting members arranged to co-operate with said longitudinal members in providing a cylindrical portion and also a conical or tapered end portion of the roll, the longitudinal members having each a flexible end portion arranged to be held in contact with a cam member mounted on a shaft at the axis of rotation of the roll, spring means being provided to hold said flexible end portions in contact with said cam members, so that the flexible ends may be operated by said cams to effect expansion or contraction of the tapered end of the roll. This movement of the flexible ends of the longitudinal members may be such as to align them with the straight portions of said longitudinal members which form the cylindrical part of the roll. By this arrangement the conical or tapered end part of the roll may be varied in inclination, that is

- in its degree of taper, relative to the cylindrical part of the roll, or be merged in said cylindrical part, thus making it possible to treat various parts of each piece of work suitably although the pieces of work may vary in size. Furthermore, the roll may have a conical or tapered portion or, alternatively, may be cylindrical throughout, in accordance with the way the work is presented or with the results desired.
- 10 As illustrated, the cam members are carried by collars at each end of the roll slidably mounted upon the shaft at the axis of rotation of the roll, the said collars being rigidly connected to each other and operable by a hand lever at one end of the roll, means such as a rack and pawl being provided for holding the hand lever and hence the cam members in adjusted position.
- 15 These and other important features of the invention and novel combinations of parts will now be described in detail in the specification and then pointed out more particularly in the appended claims.
- 20 In the drawing,
- Fig. 1 is a longitudinal sectional view through two co-operating boarding rolls;
- 25 Fig. 2 is a transverse sectional view through the rolls shown in Fig. 1; and
- Fig. 3 is a detail view.
- 30 In the illustrated embodiment of the invention, designed more particularly for performing graining and/or softening operations upon pieces of leather, there is provided a boarding roll 4 cylindrical throughout its entire length and a boarding roll 6 which may be either cylindrical throughout its length or cylindrical in an intermediate portion and with conical or tapered ends.
- 35 These rolls co-operate with each other to feed a piece of leather over an edge portion 8 of a work support 10, the rolls being power driven in the same direction as indicated by the arrows in Fig. 2, the result being that the work is moved upwardly by roll 6 and downwardly on the opposite side of the work support 10 by the roll 4 during which the leather is grained and/or softened, all as explained in detail in my co-pending application hereinbefore mentioned.
- 40 As will be evident upon inspection of the drawings, roll 6 comprises longitudinally extending boarding members 12, each of which has a frictional boarding surface provided by a layer of cork 14, although some other similar substance may be employed having a frictional quality suitable to engage with and move a piece of leather in the manner herein described. For supporting intermediate portions of the longitudinally extending members 12 there are provided supporting members 16, 18 and 20. As shown, the supporting member 18 comprises a collar 22 carried by a shaft 24 located at the axis of rotation of the roll 6. Extending in opposite directions from the collar 22 are arms 26, 28 carrying at their ends plates 30 to which may be bolted the longitudinally extending members 12. The supporting members 16 and 20 are constructed in a manner similar to the supporting member 18. However, the longitudinally extending members 12 are not secured fixedly to the supporting members 16 and 20 but, if at all, they are slidably secured to said supporting members since it is the intention to adjust the supporting members 16 and 20 lengthwise of the shaft 24 to vary the length of the cylindrical portion of the roll. For this reason the collars of the supporting members 16 and 20 are each provided with a groove to receive a key 32 which is fitted into a corresponding
- 45 groove in the shaft 24. It will be understood that the key 32 insures that the supporting members 16 and 20 will rotate with the shaft 24 while permitting sliding adjustment of the members 16 and 20 upon said shaft. As shown, the members 16 and 20 are secured in their adjusted positions by means of set screws 34.
- 50 The supporting members at the ends of the longitudinally extending members 12 not only serve as supports but also as adjusting means by which the inclination of the conical or tapered portions of the roll may be varied with respect to the cylindrical portion of the roll. For this reason supporting members 36 and 37, at opposite ends of the roll 6, comprise cam members 38 secured to or forming part of arms 40 (Fig. 2) extending in opposite directions from a collar 42 by which the supporting members 36 and 37 are mounted upon the shaft 24. As most clearly shown in Fig. 1, the supporting member 36 is connected with the supporting member 37 by means of rods 46 so that both members may be adjusted simultaneously by means provided for the purpose. This adjustment takes place longitudinally of the shaft 24, the collars 42 of the supporting members 36 and 37 being connected to the shaft 24 by means of a key and groove similar to the key and groove at 32 by means of which the supporting members 16 and 20 are slidably mounted on the shaft 24.
- 55 Preferably, and as shown, the adjusting means for the supporting members 36 and 37 comprises a manually operable lever 50 pivoted at 52 on a stationary part of the machine frame and having a forked portion 54 provided with rollers 56 receivable within a circular groove 58 in an extension 60 of the collar 42 of the supporting member 37. Upon moving the upper end of the lever 50 to the right in Fig. 1 the lower end of the lever 50 is caused to move toward the left in said figure, thereby shifting both supporting members 36 and 37 toward the left in said figure. By this arrangement the cam members 38 are operated to effect adjusting movements of the adjacent ends of the longitudinally extending boarding members 12. Conveniently, each end of each member 12 carries an anti-friction roll 62 normally held in contact with its corresponding cam member 38 by spring means comprising spring 65 (Fig. 2). It will be understood that the longitudinally extending boarding members 12 are flexible throughout the greater part of their lengths and that their extreme ends are held yieldingly pressed against cam members 38 on the supporting members 36 and 37. When the supporting members 36 and 37 are in the position shown in Fig. 1, the flexible ends of the members 12 are bent toward the shaft 24 to provide the maximum degree of taper to the conical or tapered ends of the roll 6. Upon moving the supporting members 36 and 37 to the left in Fig. 1 the anti-friction rolls 62 ride along cam surfaces 64 upon the cam members 38. By holding the supporting members 36 and 37 in adjusted position, with the rolls 62 located selectively at any one of several points along the cam surfaces 64, the degree of taper of the conical or tapered ends of the roll may be varied as desired. To accomplish this purpose the manually operable lever 50 is provided at its upper end with a pawl 66 (Fig. 3) which may be caused to engage selectively with any one of a number of teeth 68 upon a rack 70 carried by a stationary part of the machine frame. When the upper end of the manually operable lever 50 is moved to its extreme right position in Fig. 3 the cam members 38 present each a flat surface 72

to the corresponding roll 62 by which the roll 62 and the corresponding ends of the members 12 are held in a position such that the roll 6 is cylindrical throughout. In other words, the conical or tapered end of the roll has been so adjusted as to merge with the cylindrical portion of the roll. The tapered portion of the roll may be restored to any desired degree (within the range provided) by shifting the upper end of the manually operable member 50 to the left in Figs. 1 and 3. For

limiting the movement of the supporting members 36 and 37 longitudinally of the shaft 24, there is provided a collar 74 fixedly secured to the shaft at the right end of the roll in Fig. 1, and a second collar 76 fixedly secured to the shaft 24 at the left-hand end of the roll 6. In other words, the collars 74 and 76 insure that the supporting members 36 and 37 will be moved within their proper range of operative movement and not become displaced into an entirely inoperative position.

Upon inspection of the drawing it will be observed that the boarding roll 4 comprises longitudinally extending boarding members 80 carried fixedly by supporting members 82 mounted upon a shaft 84, said members 82 being in fixed relation to the shaft 84, since the roll 4 is cylindrical throughout its length and not adapted for adjustment to provide tapered portions as in the case of roll 6.

In the operation of a boarding machine embodying the boarding rolls 4 and 6 a piece of leather will be placed over the upper edge 8 of the work support 10 when the latter is in a lowered position, not shown in the drawing. Upon raising the work support 10 to operative position, as shown in Fig. 2, the piece of leather upon the supporting edge 8 is in position to be operated upon by the rolls 4 and 6 which are shown in said figure as rotatively approaching position to operate upon the work. As the boarding member 12 on the roll 6 in Fig. 2 moves upwardly, upon rotation of the roll in the direction of the arrow, it engages the leather on the work support 10 and moves it toward the edge 8 at the same time that a boarding member 80 on the roll 4 engages the work on the opposite side of the support 10 to move it downwardly away from the supporting edge 8. The result is that the leather is grained and softened by being drawn over the edge 8. As the roll 6 is shown in Fig. 1 it has a cylindrical portion of the length indicated by the line a. This cylindrical portion of the roll will engage the work more firmly, that is, with greater pressure, than the tapered portions of the roll, which are adapted to operate upon the loosely textured flank portions of the leather. By changing the roll in such manner that the tapered portions are effaced or caused to merge into the cylindrical portion of the roll, all portions of the work will receive equal pressure.

Having described my invention, what I claim as new and desire to secure by Letters Patent of the United States is:

1. In a machine for operating upon hides, skins and pieces of leather, a work treating roll having an intermediate cylindrical portion and tapered or conical end portions, and means for simultaneously adjusting the tapered end portions to vary the inclination thereof with respect to the cylindrical portion of the roll.

2. In a machine for operating upon hides, skins and pieces of leather, a work treating roll having an intermediate cylindrical portion and tapered or conical end portions, and means comprising a manually operable member for varying the

lengths of both tapered portions of the roll simultaneously with respect to the cylindrical portion thereof.

3. In a machine for operating upon hides, skins and pieces of leather, a work treating roll having an intermediate cylindrical portion and tapered or conical end portions, and means comprising a manually operable member located at one end of the roll for varying the inclinations of both tapered portions of the roll simultaneously with respect to the cylindrical portion thereof.

4. In a machine for operating upon hides, skins and pieces of leather, a work treating roll having a cylindrical portion and a tapered or conical end portion, cam members at the tapered end of the roll, and a manually operable member arranged to operate said cam members to vary the inclination of the tapered portion of the roll with respect to the cylindrical portion thereof.

5. In a machine for operating upon hides, skins and pieces of leather, a work treating roll having a cylindrical portion and a tapered or conical end portion, and cam members movable in directions lengthwise of the roll and operable to increase or diminish the diametric dimensions of the conical or tapered portion of the roll.

6. In a machine for operating upon hides, skins and pieces of leather, a work treating roll comprising longitudinally extending members, supporting members arranged for co-operation with the longitudinally extending members to form a cylindrical portion of the roll, a supporting member located adjacent to the ends of the longitudinally extending members at one end of the roll and arranged in co-operation with said ends to form a conical or tapered portion of the roll, and means comprising a manually operable member for operating the last-mentioned supporting member to vary at will the inclination of the tapered portion of the roll.

7. In a machine for operating upon hides, skins and pieces of leather, a work treating roll comprising longitudinally extending members flexible in the end portions thereof, a shaft at the axis of rotation of said roll, supporting members carried by the shaft and arranged to co-operate with the longitudinally extending members to form a cylindrical portion of the roll, a supporting member mounted on said shaft adjacent to the ends of the longitudinally extending members at one end of the roll, said end supporting member comprising cam members, means comprising a spring for holding the adjacent flexible ends of the longitudinally extending members in contact with said cam members to form a conical or tapered end portion of the roll, and a manually operable member arranged to operate said cam members to effect movement of the adjacent ends of the longitudinally extending members whereby the tapered end of the roll may be varied with respect to the cylindrical portion of the roll.

8. In a machine for operating upon hides, skins and pieces of leather, a boarding roll comprising longitudinally extending boarding members, supporting members arranged for co-operation with the longitudinally extending members to form a cylindrical portion of the roll, other supporting members located at the ends of the longitudinally extending members and arranged in co-operation with said ends to form conical or tapered portions of the roll, and means comprising a manually operable member at one end of the roll for adjusting the last-mentioned supporting members to vary at will the relative

- inclination of the cylindrical and tapered portions of the roll.
9. In a machine for operating upon hides, skins and pieces of leather, a boarding roll comprising longitudinally extending boarding members flexible in the end portions thereof, a shaft at the axis of rotation of said roll, supporting members carried by the shaft and arranged to cooperate with the longitudinally extending members to form a cylindrical portion of the roll, a supporting member on said shaft adjacent to the ends of the longitudinally extending members at each end of the roll, said end supporting members each comprising cam members, means comprising a spring for holding the adjacent flexible ends of the longitudinally extending members in contact with said cam members to form conical or tapered portions at each end of the roll, and a manually operable member arranged to operate said cam members whereby the tapered ends of the boarding roll may be varied in inclination or completely merged into the cylindrical portion of the roll.
10. In a machine for operating upon hides, skins and pieces of leather, a boarding roll comprising a shaft, boarding members extending longitudinally of said shaft in spaced relation thereto, supporting members carried by the shaft and arranged in co-operation with the longitudinally extending boarding members to form a cylindrical portion of the roll, said longitudinally extending members having flexible end portions adapted to form a conical or tapered portion at each end of the roll and each boarding member carrying at each of its ends an anti-friction roll, cam members carried at each end of the shaft and
- arranged in contact with said anti-friction rolls, spring means arranged to hold said anti-friction rolls in contact with said cam members, rods connecting the cam members at one end of the roll with those at the other end of the roll, and a manually operable member arranged to effect simultaneous movement of the cam members at both ends of the roll whereby the tapered portions of the roll may be varied with respect to the cylindrical portion thereof.
11. In a machine for operating upon hides, skins and pieces of leather, a boarding roll comprising a shaft, boarding members extending longitudinally of said shaft in spaced relation thereto, supporting members carried by the shaft and arranged in co-operation with the longitudinally extending boarding members to form a cylindrical portion of the roll, said longitudinally extending members having flexible end portions adapted to form a conical or tapered portion at each end of the roll and each boarding member carrying at each of its ends an anti-friction roll, cam members carried slidably at each end of said shaft and arranged in contact with said anti-friction rolls, spring means arranged to hold said anti-friction rolls in contact with said cam members, rods connecting the cam members at one end of the roll with those at the other end of the roll, and a manually operable member at one end of the roll arranged to effect simultaneous sliding movement of the cam members at both ends of the roll whereby the tapered portions of the roll may be expanded or contracted diametrically to vary at will the relative inclination of the cylindrical and tapered portions of the roll.

KARL RAUSCH.
